DESIGN FOR A LAMPPOST

Eddy Lamb and Clair D. Freeman,
Los Angeles, Calif.

Application January 3, 1947, Serial No. 135,933

Term of patent 7 years

(Cl. D48—31)

To all whom it may concern:

Be it known that we, Eddy Lamb and Clair D. Freeman, both citizens of the United States, residing at 1131 No. Larrabee Street, Los Angeles 46, in the county of Los Angeles and State of California, have invented a new, original, and ornamental Design for a Lamppost, of which the following is a specification, reference being had to the accompanying drawing, forming a part thereof.

We claim:

The ornamental design for a lamppost, substantially as shown.

EDDY LAMB.
CLAIR D. FREEMAN.
